GEORGES ROMANE, OF ST. MANDE, FRANCE

ARTIFICIAL FUR

Application filed February 24, 1928, Serial No. 256,678, and in France May 19, 1927.

The present invention has for its object the provision of an improved product which will imitate furs in general and more particularly those characterized by irregularities in the length, texture or arrangement of the hairs, such as, for example, monkey, skunk, fox, mink, etc.

This product is obtained by manufacturing in any suitable way, as by knitting, 10 weaving, crocheting, etc., either by hand or by machine, a fabric formed of, or comprising, loops or small rings of any suitable shape, size and arrangement. The loops or rings (hereinafter merely termed 15 "loops") are subjected to a scratching, scraping, combing, carding, or like operation, which is subsequently referred to simply as "carding", without, however, severing them, so that the fibers or hairs will 20 be straightened out little by little by being caused to slide over one another, in the case of fibers having sufficient resistance for that purpose, or will be snapped off at different lengths if they are frail or are of continuous 25 character.

In order to obtain imitations of certain furs, such as beaver, Mongolian goat, mouflon, etc., characterized by more or less marked curls or wavings, the fabric may be 30 constituted by threads of the type known as "looped", representing a chenille, the fibers of which would not have been cut. These looped threads are subjected, as above stated, to a carding or analogous treatment, 35 previous to which a clean severing may be effected. Goffered, waved or curled threads can also be used to form the loops, as well as ordinary threads which, after the loops have been formed and then opened, 40 can be subjected to goffering, waving, curling and similar treatments. Ordinary threads can, moreover, be mixed with any of the above-described special threads; and in any case the looped fabric can be applied 45 to a suitable backing of fabric, skin or other material, and can undergo watering, goffering or other operations of like character for ornamental purposes, as well as dyeing, glossing, etc., either before or after its 50 application to the backing.

The accompanying drawing shows, by way of example, certain details of the invention, the figure therein representing a looped thread attached to a support.

The drawing shows a form of type of looped thread *b* which can be utilized, to form the loops. This thread comprises a core *c* around which the loops proper are spirally arranged, and to which they are connected; in which respect they are distinguished from ordinary looped threads which, not being held by a core, resume their rectilinear form so soon as a certain traction is exerted on them, whereas the presence of the core prevents the loops from straightening out. 55 The thread thus formed is made into a loop and then fastened to a weft thread *d* or other support, as in the first case; and afterward the loops are opened in the same way 60 as before. 65

I claim as my invention:

An imitation fur, comprising a support having carded looped threads attached thereto, each such thread itself embodying a multitude of small loops connected to a 70 core. 75

In testimony whereof I affix my signature.
GEORGES ROMANE.
